UNITED STATES PATENT OFFICE.

BASIL E. CRAMPTON, OF GRAND RAPIDS, MICHIGAN, ASSIGNOR TO WINTERS, STREYKER
& CRAMPTON, OF GRAND RAPIDS, MICHIGAN, A CORPORATION OF MICHIGAN.

HINGE.

Application filed February 16, 1925. Serial No. 9,436.

This invention relates to a hinge and one which is of particular utility in connection with refrigerator doors, though in no sense limited to the one field of use. It is a primary object of the present invention to construct a hinge which may be applied to doors or other swinging objects designed to be hingedly mounted, and which is made from two major parts and so constructed that each 10 is readily formed from sheet metal by means of proper blanking and forming dies and in each of which the finishing of the outer sides of the hinge members is very economically attained by reason of the construction of 15 such members, whereby buffing and polishing the same for nickelizing and for polishing after nickelizing is easily accomplished on account of the surfaces of the members being readily engaged by buffing or polishing 20 wheels. A further object of the invention is to construct a hinge which may be readily fitted to doors, such as refrigerator doors, wherein, due to discrepancies in the dimensions of the doors with respect to the casings which they fit it is necessary many times 25 to bend or malforn the hinge to take care of the variations. This is accomplished in hinges, ordinarily, by striking one member of the same with a hammer so as to bend 30 the hinge to compensate for any discrepancy there may be in the fit of the door to the door casing. In most hinges it is necessary to strike and thus bend the hinge at the outside or on a nickelized polished surface, 35 with the result that the nickel is dented or otherwise marred and in many cases is broken from the body of the hinge underneath. In the present invention the construction is such that this adjustment is made by striking 40 a member of the hinge on an under side which is not seen and which is not polished and on which any dents or mars made are of no consequence. Various other objects and purposes than those stated will appear 45 as understanding of the invention is had from the following description taken in connection with the accompanying drawing, in which,

Fig. 1 is an elevation of the hinge, a part 50 of one member being broken away and shown in section for better disclosure of the invention.

Fig. 2 is a longitudinal section through the hinge construction shown in Fig. 1.

Fig. 3 is a perspective view of one member 55 of the hinge.

Fig. 4 is a perspective view looking at the under side of the other member of the hinge, and

Fig. 5 is a section through a fragmentary 60 portion of a door and door casing and showing the hinge used to mount said door on the casing and with the door in the position to which it is moved when adjustment of the hinge to fit the door to the casing opening 65 is required.

Like reference characters refer to like parts in the different figures of the drawing.

In the construction of the hinge one member, indicated at 1, is made from sheet metal and has a substantially flat outer side, at one end being formed with a curved inwardly projecting end 2, around its sides and other end edges being formed with an integral 70 75 inwardly extending flange 3 which, at each side and adjacent the end where the curved section 2 is located, is widened to make relatively wide ears 4, as shown. This member of the hinge, it will be noted, has a broad and flat outer surface which may be readily buffed and polished and the outer sides of the flanges 3 and ears 4, as well as the outer side of the curved section 2, may be conveniently reached by a buffing or polishing 80 85 wheel so that the finishing of the hinge member is accomplished with a minimum of effort.

The other member of the hinge comprises a plate 5 which may be outwardly dished for 90 purposes of reinforcement and which, at its inner end, has a projecting outwardly curved section 6 integral with the plate 5, continued in a return bend 7 from which a section 8 extends backwardly and outwardly at an angle 95 to the plane of the plate 5 and terminates in a pintle receiving roll 9 as shown, the same being located substantially over the junction of the section 6 with the plate 5. The part of this hinge which has to be buffed and polished and finished, that is the plate 5, is readily accessible for the necessary buffing and polishing operations.

The hinge member 1 is placed over the sections 6, 8 and the roll 9 with the ears 4 located one at each end thereof. A pintle rod 10 is passed through openings in the ears 4 and through the roll 9, its ends being riveted

- over to make a permanent and secure connection of the two hinge members as is evident. When thus assembled the sections 6 and 8 and the bend 7 and roll 9 are covered from view.
- 5 When the hinge is attached to a door and door casing the hinge member 1 is fastened to the door 11 by screws or other suitable fastenings and the hinge plate 5 similarly attached to one side of the door casing 12, as shown in Fig. 5. Many times in fitting the door to the door casing, due to too much removal of material at the "rise" in the door, indicated at 11^a, the inner side of such portion does not come into sufficiently close contact with the outer side of the door casing. When this occurs it is necessary only to turn the door to the position shown in Fig. 5, in which case the door is wide open, and strike the part 8 with a hammer so as to bend it closer to the inner portion of the hinge. Inasmuch as the side of the part 8 thus struck by the hammer is always out of sight except when the door is fully open (and this occurs only infrequently and for very short periods of time), any denting or marring of this portion of the hinge is of little or no consequence; while the outer exposed sides and parts of the hinge are not injured in any manner in effecting the proper fit and adjustment of the door to the casing opening. This is one important feature of the invention and combined with the simplicity of construction and the ease of finishing the parts, together with the attractive appearance presented by the hinge make the invention one of great merit. The invention is defined in the appended claims

and is to be considered as comprehensive of all forms of structure coming within their scope.

I claim:

1. In a hinge, a hinge member comprising a plate formed at one end with an outwardly bent section which is turned back upon itself in a second section located a distance outward from the first section and terminating in a pintle receiving roll, a second hinge member formed as a substantially flat plate and having an inturned flange at its sides and one end, said flange at each side and adjacent the opposite end of the plate being widened to form ears adapted to pass one at each end of the roll, and a pintle passing through said ears and roll for pivotally connecting the hinge members together, said plate of the second hinge member at the end thereof where said ears are located being formed with an inturned curved extension located over and covering the outer portion of said roll, substantially as described.

2. In a hinge, a hinge member comprising a plate formed at one end with an outwardly bent pliable section which is turned back upon itself in a second section terminating in an eye spaced away from said plate and a second hinge member pivotally attached to the said back turned section by a pintle extending through said eye, said second hinge member normally lying over and covering said outwardly bent section and back turned portion thereof.

In testimony whereof I affix my signature.

BASIL R. CRAMPTON.
